ELECTRIC STEAM IRON

Edward P. Schreyer, Ridgefield, Conn.

Application May 5, 1953, Serial No. 353,067

8 Claims. (Cl. 38—77)

The present invention relates to electric steam irons of the in-built boiler type.

A general object of the invention is to provide an electric steam iron that can be made with economy of materials and workmanship, with a minimum number of parts, and in which access is had to the filling opening without resort to or manipulation of screw plugs or other hot parts, without resort to tools and without the need for a separate filling funnel or other auxiliary equipment, and in which the steam dome need not be separately fabricated or blanked out apart from the boiler and soldering, welding or brazing operations are dispensed with for installing such steam dome upon the boiler, as is also the need for any filling opening distinct from such steam dome.

Where electric steam irons, and especially the boiler structure thereof, are of aluminum or aluminum alloy, any water, even a film of water remaining in the boiler after use is likely to cause corrosion, for which reason it is among the objects of the invention to provide an electric steam iron structure such as one of aluminum, which not only affords convenience in charging its boiler with water and doing so safely, even while the iron is hot, but which also affords facilities for readily pouring out any remaining water after use of the iron, without the likelihood of trapping water, which more particularly affords convenient and secure means for safely handling the iron without strain to permit such emptying operation, and which conveniently permits complete drying of the iron thus drained.

One feature of the invention is the incorporation of the boiler filling opening in the steam dome, for which purpose the filling opening has a movable closure affording a vapor-tight seal to form a leak-tight steam dome, so that upon opening of said closure, water may be poured through the region of the steam dome into the boiler.

While within the scope of a broader aspect of the invention, the filling opening of the electric steam iron could be in the form of a filling well such as shown in my prior Patent 2,475,572, granted July 5, 1949, with the closure for the steam dome releasably seated at a silicone plastic gasket, it is preferred, more especially where the boiler is of aluminum, so to form the boiler top that the filling opening will serve also as a discharge opening for pouring out therethrough any remaining water after use, thereby to guard against the danger of corrosion of such boiler due to storing it away with water in it.

To this end the filling opening, according to one feature, instead of being a well extending downward into the boiler body, rises from the general area of the top of the boiler, preferably in the form of an upturned frustoconical wall stamped as a unitary part of the boiler shell, the circular rim at its top serving as the outlet of a funnel when the iron is inverted to permit emptying without the danger of trapping any water. Where the combined filling and discharge opening rises from the top of the boiler, as is preferred, the closure therefor

which with the upstanding wall, forms the steam dome, may be in the form of a cap, the side wall of which carries and encompasses a ring, preferably of silicone plastic to afford the seal.

- 5 Insulating handle or grip means may be movably and preferably hingedly mounted for raising the closure to permit filling, and means is provided for latching such handle to normal position after filling, in which the closure is in operative position. Resilient means carried by such handle means retains the closure against its seat, not only to render the steam dome leak-tight in use, but to permit it to vent whenever steam pressure tends to accumulate in the boiler.

This insulating grip means may be movably and preferably hingedly mounted and latched in outermost position with respect to the iron handle or grip by which the user may hold the iron in inverted position with the filling opening lowermost for purposes of draining therethrough any water remaining in the boiler.

20 Preferably the handle of the iron itself serves in addition to its primary function, the further functions of mounting the closure for the filling opening and of serving as the grip for holding the iron in substantially inverted position securely latched with respect to the iron body for the desired drainage.

25 In a preferred construction, the handle of the iron carries latch means desirably at its forward leg for retaining the handle in normal position for ironing and contains further latch means at its rear leg that becomes operative when the handle is tilted backward as far as it will go, to latch it with respect to the iron structure so as to permit the user comfortably to hold the iron in inverted position for drainage. A single finger operated member, desirably a push button near the front of the iron is connected by a transmission within the handle for release of either closed latch means and is preferably spring-urged for automatic closing of the front latch when the handle is in normal position, and of the rear latch when the handle is tilted back as far as it will go.

30 40 In the accompanying drawings in which is shown one of various possible embodiments of the several features of the invention,

Fig. 1 is a view in longitudinal cross section through a preferred embodiment of the present invention, showing the open position of the handle in dot and dash lines,

Fig. 2 is a fragmentary transverse sectional view on a somewhat smaller scale, taken on line 2—2 of Fig. 1,

Fig. 3 is a perspective view of the lower handle hinge plate and the parts affixed thereto,

Fig. 4 is a view similar to Fig. 3, of the upper handle hinge plate,

Fig. 5 is a perspective view of the latching eye near the front of the handle,

Fig. 6 is a view in transverse cross-section on a somewhat larger scale than in Fig. 1, of the boiler closure unit,

Fig. 7 is a perspective view of the open iron in position for drying out any water remaining in the boiler, and

Fig. 8 is a detail sectional view of an improvement, shown on scale larger than in Fig. 1.

Referring now to the drawings, the iron comprises a boiler B which may be of any suitable sheet metal but is desirably of aluminum and comprises a body shell 10, the rim 11 of which encompasses and is bonded to the downturned flange 12 of the floor plate 13.

The body shell affords room under floor plate 13 to the rear of the boiler, for accommodating the thermostat 15 which is mounted upon the rear part of the sole plate 16, the upright adjusting rod 17 therefor rising through an aperture 19 to the rear of the boiler, the rear wall of

which is determined by the upturned rear portion 14 of floor plate 13 which is welded to the side and top of the body shell 10. Rod 17 is controlled by a suitable knob 21 accessible from the rear part of the iron for adjusting its temperature to the fabric being ironed.

The electric heating element 23 is preferably molded into the sole plate 16. The boiler floor may be secured to the sole plate in face to face relation therewith by suitable means, desirably by Riv-nuts 24 of familiar construction, the coating screw element 25 of each of which is accessible through a corresponding aperture as at 26 in the bottom of the sole plate 16. Thus the heater 23 is in heat conducting relation to both the sole plate and the boiler.

Rising from near the forward end of the boiler is the steam tube 27, the lower end of which may constitute a Riv-nut. A little ring 29 of silicone plastic in a corresponding depression in the sole plate renders leak-tight the joint at the lower end of the steam tube. The upper end of the steam tube 27 may be pinched together at 27' above one or more apertures 27^a, near the upper end of said tube.

The steam tube 27 is desirably not axially of the filling opening 31, but its upper end is near the rim of said opening at one side as shown, to afford a wide space with respect to the opposite side of the rim for adequate venting in filling. Desirably also a baffle wall 38' of width little greater than that of the steam tube is welded to and extends downward slightly from the top of the boiler shell 10 to intercept any water that might otherwise splash through apertures 27^a into the steam tube.

The sole plate 16 has a triangular depression 32 in its lower face that has communication with the lower end of the steam tube 27, and discharges the steam to the fabric being ironed, by way of ports or slits 33 in closure plate 34 for the depression 32, and that closure plate is detachably secured in place as by an upstanding screw 35 threaded into and countersunk in the bottom of the closure plate 34.

A baffle plate 36 extending across the entire area of the forward half of the boiler, sloping downward slightly from front to rear and through which the steam tube 27 extends, as shown, has a bordering flange 37 soldered or brazed to the body shell. Desirably the rear end of the baffle plate 36 has an upstanding wall 82 and in front of said wall has one or more apertures 83 to drain any water lodged upon said plate when the water remaining in the boiler does not reach up to said plate.

Preferably the baffle plate 36 is depressed slightly downward at the region about the steam tube 27 to present a flat circular marker 84, readily visible through filling opening 31 as an indication when to stop filling.

All of the welding operations, including those by which the floor plate 13, the baffle plate 36, the rear wall 14 of the boiler and the baffle wall 38' are bonded to the body or boiler shell 10, are readily and expeditiously performed by oven-heat which causes the requisite flow of an inner flowable lamination 10' of the sheet metal stock of body shell 10.

In the embodiment shown, the boiler filling conformation is also rendered effective for emptying the boiler, by simply conforming it to rise as a frusto-conical wall 38 from the upper part of the boiler and as an integral part of the boiler shell stamping, the upper rim 31 of said rising wall being the filling and emptying opening.

A heat insulated carrier, desirably a movable arm 85, serves effectively to accommodate and removably to mount a closure unit C for the filling opening 31, and serves also as a hand-hold to remove such closure from its seat. That carrier, which is desirably the handle proper of the iron may be molded of plastic, and comprises in addition to base or arm 85 the forward and rear legs L that rise therefrom and the connecting grip portion G.

A closure mounting sheet metal plate 39 countersunk

within the lower face of the handle, is affixed thereto as by screws 40 and affords a keyway slot 41 therein for accommodating the shank 42 of the closure unit C. The enlarged head 43 of the closure shank may readily be introduced through and then pushed therealong from the enlarged end of the keyway slot, and thus be retained in place by the pressure of the conically helical coil spring 44 encompassing the shank 42 and confined at its upper end within conical slideable cap piece 45, urged upward by the spring against head 43. The handle may be hinged to the body of the iron by means of a hinge at its rear. That hinge may comprise a lower leaf 46 screwed into a corresponding depression in the upper face of the rear end of the body structure, connected by pintle pin 47 to an upper hinge leaf 48, affixed as by screws 49 to lateral lugs 50 in the lower face of the handle. The shoulders 47' of the molded handle base keep the pintle in place.

The closure itself is desirably a sheet metal cap 51 to which the lower end of shank 42 is axially welded and it carries a yielding ring 52, preferably of silicone plastic, lodged within its peripheral depending bead 53, resiliently to seat against the outer surface of the frusto-conical wall 38 under pressure of spring 44, when the handle is closed as shown in Fig. 1. The head 43 of shank 42 is accommodated in a small depression 43' above plate 39 in the arm 85 of the handle H.

The handle is releasably retained in closed position by means of a latch, preferably comprising a small angle bracket 54, the latching eye 55 of which is upright, its upper end 54' being preferably inclined backward so as to act as a lead or guide for the coating latch hook 58. The mount 56 of bracket 54 is affixed in countersunk relation to the roof of the boiler in front of the filling opening, as for instance by means of a Riv-nut 57. A latching hook 58 on the handle coacts with latching eye 55 on the boiler. Latching hook 58 is at the lower end of a lever 59 which is pivoted in an eye 60, desirably formed at the forward end of the closure mounting metal plate 39. Any suitable spring means may retain the latch hook 58 in closed position and release may be effected when desired by suitable means, one illustrative embodiment of which will be more fully described hereinafter.

According to the invention, latch means is also provided at the rear of the iron body that is normally open but becomes effective to latch the handle in fixed open position and preferably such latch limits the movement of the handle to its most rearwardly tilted position. Illustratively the fixed rear latch member is an upstanding arcuate flat bar 61 concentric with the hinge pivot 47 and having a latching notch 62 near its upper end and riveted in place as at 63' between lateral or flanking plates 63 of greater width. Lateral plates 63 are desirably angle plates, the bases 65 of which are welded as at 64 to the lower or body hinge leaf 46. Coacting with latching bar 61 is a latching hook 66 at the lower end of lever 67. Lever 67 is pivotally mounted on pin 68 bearing at its ends in indentations 69^a of plates 69 that rise from and are affixed at angle extensions 69' welded to the upper hinge plate 48 that mounts the handle.

When the handle is moved rearward, the rear latching hook 66 rides between the wider flanking plates 63 as a track along the arcuate edge therebetween of the latching plate 61 against which it is urged by a suitable spring to be hereinafter described, until it registers with the notch 62 into which it is automatically snapped by such spring, thereby securely to retain the handle in the rearwardly latched position shown in dot and dash lines on Fig. 1, for convenience in holding the iron in inverted position to drain any remaining water from the boiler.

While in the broader aspects of the invention, the rear latch could be independent of the front latch, and while the handle or grip for holding the iron in inverted position for emptying could be independent of the handle proper of the iron and could be latched in extended position for emptying by any suitable means, it is much to

be preferred to control the operation and release of both the front latch for maintaining the handle in normal operative position and the rear latch for retaining the handle in rearwardly tilted position for convenience in emptying by one and the same readily accessible instrumentality, desirably a finger operated member, preferably one operated by simple thumb pressure. To this end the iron handle is desirably of hollow construction, affording at the hollow top of its main structure, facilities for accommodating a transmission therewithin that interconnects the movable front latch arm 59 and the movable rear latch arm 67. The hollow handle has a separate molded plastic cap-piece 79, to complete the hollow grip and confine the transmission. That closure piece may be removably attached to the handle body by means of screw 80 through a ledge in the rear leg of the handle and by one or more of the screws 40 at the front which serve for attaching plate 39.

Desirably the transmission within the hollow handle comprises a link 70 consisting of a flat bar pivoted at 72 at its downwardly inclined forward part 71 to the upper end of front latching lever 59 and pivoted at its rear end as at 73 to the upper end of the longer lever 67 of the rear latch member 67. The connecting link 70 is desirably guided between several pairs of upstanding lugs 74 molded as part of the lower half of the hollow handle grip that is an integral part of the main handle structure. A coil spring 75 encompassing said connecting link and interposed between one pair of said upstanding lugs 74 and a shoulder 76 on the link urges that link forward to spring-urge forward the upper end of lever 59 and thus urge inwardly the forward latch 58 toward the locking position shown in full lines in Fig. 1. By such forward movement of link 70, the upper end of lever 67 is also moved forward, thus to urge inward the rear latch 66 toward locking position.

When the handle is in closed position, the forward latch 55—58 is locked and the hook 66 of the rear latch, while urged inward as set forth, is directly below the lower end of the complementary arcuate latching bar 61.

For operational control of both latches of the iron, a push button 77 is preferred, which protrudes from between the main handle structure and the separate plastic cap piece 79 at the forward leg of the iron handle. While push button 77 may be connected to the link by a separate bar, it is preferably connected by a bar extension 78 unitary with link 70 to the pivot pin 72 that connects the connecting link 70 to the upper end of the forward latch lever 59.

The operation of the electric steam iron of the present invention will be readily understood.

In order to charge the boiler, the operator grasping the handle in normal manner merely presses the push button 77 inward with her thumb against the resistance of coil spring 75, thereby to pivot the lower hook end 58 of latch lever 59 outward for opening the forward latch, and she tilts the thus released handle backward about its pivot 47. In that tilting action the hook end 66 of the rear lever 67 will ride between the flanking plates 63 along the arcuate edge of the rear latching bar 61, and pressure on the push button being released, the coil spring 75 will cause the rear latch hook 66 to snap into the latch notch 62 of said bar 61 when registry is reached, thereby to latch the handle into its extreme back-tilted position shown.

The filling opening 31 being now fully exposed, water may readily be poured into the boiler. Such admission, even while the iron is hot, occurs without the ejection of hot water or steam that might injure the user. For the filling opening 31 is of wide area and the upper end of the steam tube being near one portion only of the rim 31 affords ample admission and venting space.

It is of course not necessary to tilt the handle back to its extreme latched position for filling, but ordinarily this

would be done to guard against the handle dropping back to closed position by gravity during filling.

The closure C being mounted in slot 41 is self aligning with the frusto-conical wall 38 and its yielding ring 52 being of inner diameter larger than that of rim 31, the seating of the closure is accurate and effective, without the danger of said ring striking the sharp edge of the rim 31, and the expansion of ring 52 is limited by the bead 53 of the closure cap, thus assuring a tight seal during use.

The steam generated within the boiler during use collects in the steam dome made up of the rising wall 38 and the closure cap 51 thereof, from which steam passes through lateral apertures 27a in the steam tube 27 down to the steam chamber 32 for escape through the steam holes 33 in the sole plate 16.

Should steam pressure tend to develop within the boiler, it is manifest that it will cause the closure cap C to rise slightly for venting and for ready escape laterally beyond the front and sides of the base plate 85 of the handle.

Upon completion of the ironing, it is desirable to empty out any remaining water, especially where the boiler is of aluminum which is especially subject to corrosion should water remain stagnant therein for any prolonged period. While the water could be ejected by continuing the heating of the iron, tilted slightly forward, and allowing the steam to force the water out through the apertures 33, that operation is slow and somewhat hazardous.

According to the present invention, removal of any water from the boiler is facilitated. The handle when latched in open position, as above described, forms a convenient hand grip for holding the iron in inverted position in order to allow the remaining water to escape through the opening 31, which escape occurs without any danger of trapping water as would be likely were the filling opening in the form of a depressed filling well. Thus even though the heating element be burned out and the iron dead, the water remaining in the boiler may be readily discharged therefrom, which is all but impossible with familiar types of electric steam irons.

If desired, the iron may be rested with its handle latched in open position, in butterfly fashion, as shown in Fig. 7, the sole plate resting on its rear edge, being thus tilted upward to one side and the open handle resting on its upper rear edge is tilted upward to the other side. Thus retained, the iron could remain plugged in to heat it for a short period of time and evaporate any remaining film of water preparatory to re-closing the handle as previously indicated and putting the iron away.

To return to closed position, the handle, latched in open position as described, the user merely presses the push button 77 against the resistance of spring 75, thereby releasing the rear latch by lifting the latch hook 66 out of notch 62 and the handle is then returned to closed position, when the spring 75 will expand, again to close the forward latch, resiliently to maintain closure C over the filling opening for ironing.

Immediately after pressing push button 77 to open the forward or the rear latch, as the case may be, only slight movement of the handle is effective to keep the push button depressed. For as long as latch hook 66 rides along, arcuate latch bar 61, spring 75 cannot expand until said hook reaches notch 62 when thumb piece is snapped outward. Similarly only when such hook 66 passes downward beyond the lower end of arcuate bar 61 and latching hook 58 registers with eye 55 is spring 75 released to snap the forward latch closed and urge push button 77 outward.

Even though in the course of use, the handle H be slammed down hard to closed or latching position, no distortion or other injury to the iron or to its latch 55—58 can result. This will be apparent from the fact that the coil spring 44 resiliently absorbs the shock of such slamming closure, and only when position of full closure has been reached does rear latching hook 66 clear the arcuate

bar 61, as shown in Fig. 1, to release spring 75, and only then will hook 58, now in registry with eye 55, be urged by spring 75 to enter such eye.

Thus according to the invention, a rugged electric steam iron is provided with a minimum number of parts that are easily assembled, without the need for elaborate welding operations, and in fact that requires merely oven-welding for affording the leak-tight boiler construction, which affords facilities for ready and safe filling, even when hot, without the need for separate filling funnels or other auxiliary equipment or tools, which inherently precludes building up of hazardous steam pressure therein, and which may readily and completely be emptied after ironing, and thus the iron becomes substantially proof against corrosion by even a film of moisture that might remain therein when it is stored away after use.

The steam that enters the steam chamber 32 from steam pipe 27 may become heated further by exposure to heat from the contiguous heating element 23, and thus reach excessive temperature.

The embodiment of Fig. 8 in which corresponding parts have the primed reference numerals of those of Fig. 1, serves to overcome such difficulty.

Referring to Fig. 8 there is interposed between the steam chamber 32' and the bottom of the sole plate 16' thereabove a sheet 90, extending substantially the full area of the chamber 32' but turned upward at 90' at its rear end to afford a guide for directing the steam from the steam tube 27' downward under said sheet 90 and thereby interposing between the steam in said chamber and the bottom of the sole plate and intervening heat insulating air space 91 which is maintained by a series of teats 92 extending downward from the sole plate thereabove. A screw 35' through closure plate 34' through a sleeve 94, presses the sheet 90 in place against hub 93 in the sole plate. The sheet may be of metal such as aluminum of about .01 inch thickness which affords sufficient stiffness for the purpose, or if desired, it may be of insulating material such as a glass wool panel.

As many changes could be made in the above construction and many apparently widely different embodiments of this invention could be made without departing from the scope of the claims, it is intended that all matter contained in the above description or shown in the accompanying drawings shall be interpreted as illustrative and not in a limiting sense.

Having thus described my invention what I claim as new and desire to secure by Letters Patent of the United States is:

1. An electric steam iron of the type comprising a sole plate, a boiler affixed thereon and having a filling opening in its roof, electric heating means in heat conductive relation with both the sole plate and the boiler and a steam dome at the roof of the boiler and extending over the upper end of a steam tube rising from the floor of the boiler; the combination in which said steam dome comprises a removable spring-urged closure unit and a seat therefor peripherally of said filling opening, said iron having a hinged handle, a metal mounting key-hole plate affixed in a corresponding depression in the bottom of the handle, said plate having an elongated slot therethrough aligned with the longitudinal axis of said handle and enlarged at one end, said closure unit having a shank with an enlarged head of dimensions less than that of the enlarged end of said slot and greater than the remaining portion of said slot to be retained thereby to mount said closure unit, said handle serving for manually displacing said closure to permit filling of the boiler through said opening, and a gasket ring affixed peripherally of one of the coacting elements that constitute the steam dome closure and the seat therefor, and means upon said boiler releasably to latch said closure carrier for maintaining a leak-tight seal between the closure of said steam dome and the seat therefor.

2. The combination recited in claim 1 in which the upper end of the steam tube is adjacent one part and substantially spaced from the diametrically opposite part of the rim of the filler opening, and in which the upper extremity of said steam tube is closed and said steam tube presents one or more lateral openings therebelow.

3. An electric steam iron comprising a sole plate, a boiler affixed thereon, electric heating means in heat-conductive relation with both said sole plate and said boiler, said iron having a handle pivotally mounted thereon near the rear end thereof, means for releasably retaining said handle in normal ironing position, said handle having a spring-urged closure mounted thereon for coaction with a filling opening in the roof of said boiler, exposed for filling when the handle is moved away from normal position, and means under control of the handle for latching it in open position for convenience in holding the iron inverted for emptying its boiler, said means comprising a fixed rising arcuate latching bar concentric with said pivot mount and having a latching notch, said handle having a pivoted spring-urged latching hook to coact with said latching notch in extreme open position of the handle.

4. An electric steam iron comprising a sole plate, a boiler affixed thereon, electric heating means in heat-conductive relation with both said sole plate and said boiler, said iron having a handle pivotally mounted thereon near the rear end thereof, means for releasably retaining said handle in normal ironing position, said handle having a spring-urged closure mounted thereon for coaction with a filling opening in the roof of said boiler, exposed for filling when the handle is moved away from normal position, and means under control of the handle for latching it in open position for convenience in holding the iron inverted for emptying its boiler, said means comprising a fixed rising arcuate latching bar concentric with said pivot mount and having a latching notch with flanking plates against opposite faces thereof protruding therebeyond, said handle having a pivoted spring-urged latching hook movable between said flanking plates to ride along the arcuate edge of said latching bar and to coact with said latching notch in extreme open position of the handle.

5. An electric steam iron comprising a sole plate, a boiler affixed thereon, electric heating means in heat conductive relation with both said sole plate and said boiler, a handle pivotally mounted at its rear to the body of the iron and having a spring-urged closure mounted thereon for cooperation with a filling opening in the roof of the boiler, means for latching the handle in closed position for normal use of the iron, and means for latching the handle in rearwardly tilted open position for convenience in holding the iron inverted to drain water therefrom, a single finger-operated element on the handle for controlling the forward and the rear latch when the handle is closed and in wide open position, respectively, and a transmission between said finger-operated element and both the forward and the rear latch for releasing the front latch preparatory to opening the handle and for releasing the rear latch preparatory to re-closing the handle.

6. The combination recited in claim 5 in which the front latch comprises an angle bracket rising from the boiler and presenting a latching eye, the handle is hollow and accommodates a latching lever pivoted therein with a latch hook for coaction with said eye, in which the rear latch comprises an arcuate latch bar rising from the iron body, concentric with the pivot mount of the handle and having a latching notch therein, in which a coacting lever has a latching hook at its lower end and is pivotally mounted in the rear leg of the handle and in which a link extending longitudinally through the hollow handle is pivotally connected to the upper ends respectively of the forward latch lever and the rear latch lever, in which a spring urges the connecting link forwardly

to pivot both forward and rear levers inwardly toward latching position, and in which a push button accessible at the front of the hollow handle is connected to the forward end of the connecting link for moving out of the path of the coacting eye and notch, the forward and rear latching levers, respectively.

7. The combination recited in claim 5 in which the latching means includes rising latch members affixed near the front and rear respectively of the iron body, in which the handle is hollow and has mounted a pivoted latching lever in its front leg and a pivoted latching lever in its rear leg, in which the transmission comprises a link extending longitudinally within the hollow handle grip portion and pivoted near opposite ends to the upper parts of the respective latching levers, in which spring means coacting with the link urges both latching levers inward toward latching position, in which the rear latching lever is out of registry with the associated rising latching member when the handle is in closed position, and in which the finger-operated member is accessible through the hollow body for overcoming the pressure of the spring means and simultaneously moving both latching levers from latching position so as to release the front latch preparatory to opening the handle and by the same operation to release the rear latch preparatory to re-closing the handle.

8. The combination recited in claim 7 in which the connecting link is mounted between upstanding guides in the hollow handle grip portion, and in which the upper portion of the hollow handle grip portion is a separate cap piece removably affixed near its front and near its rear to the main handle body and in which the finger-operated member is a push button which protrudes at the front of the handle from between the two parts of the handle.
